FLIER CONSTRUCTION

Michael J. McHale, Scranton, Pa.

Application July 11, 1939, Serial No. 283,880

15 Claims. (Cl. 57—116)

My invention relates to fliers of the type used with spinning machines, and more particularly to a flier block arrangement having improved means for attaching and supporting the flier wires.

One of the objects of the present invention is to provide a flier structure particularly adapted for use with bobbins of the type wherein comparatively large head members are used. Heretofore, and prior to the adoption of bobbins having large head portions, the desired uniform tension could be maintained on the thread during the winding operation by means of conventional fliers. It has been found, however, that conventional fliers are not adaptable for use with large bobbins since, by reason of their inherent construction, uniform tension on the thread cannot be obtained.

It will be appreciated that by increasing the diameter of the bobbin head, it became necessary to lengthen the flier wires, the increased length thereof being reflected in the distance from the point of attachment of the wire to the flier block outwardly to the drop arm or the thread receiving eye. Since this substantially horizontal portion of the flier wire arm is unsupported, the wire is obviously easily flexed out of the mean horizontal plane, resulting in considerable variation of tension on the thread. It will also be appreciated that during the winding operation increased tension on the thread, due to the variation in the angle of take-off, frequently causes the flier wire arm to be pulled down into contact with the upper surface of the bobbin head.

After considerable research and experimentation, I have found that the desired uniform tension, when large bobbins are used, can be maintained at all times during the winding operation, if the flier block is constructed and arranged to provide additional support for the flier wires between their points of attachment to the flier block and the dropped arms or eyes, together with means for guiding the thread in a path substantially perpendicular to the plane of the flier wire arms, irrespective of the variation in the angle of take-off of the thread.

An object of my invention is to provide a flier for spinning machines and the like adapted for use with bobbins having relatively large head portions.

Another object of my invention is to provide a flier block having improved means for attaching and supporting the flier wires thereon.

Yet another object of my invention is to provide an improved flier for spinning machines and

the like having means associated therewith adapted to guide the thread in a fixed path of travel to the flier wires, irrespective of the angle of take-off from the bobbin.

Still another object of my invention is to provide a flier construction having means whereby the arms of the flier wires are supported in a fixed plane in the vicinity of their points of attachment to the flier block.

A further object of my invention is to provide an improved flier construction wherein the flier wires are attached to the flier block by twisting or entwining the arms thereof, portions of the arms beyond the points of attachment being supported in a fixed plane whereby undesirable flexing of the flier wires about their points of support is prevented.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is an elevational view, partly in section, showing my improved flier in operative position on a bobbin spindle.

Figure 2 is a plan view of the flier shown in Figure 1.

Figure 3 is a plan view of the bottom of the flier shown in Figure 1.

Figure 4 is an expanded perspective view of the parts of the flier block.

Figure 5 is an elevational view, partly in section, showing a flier mounted in operative position on a bobbin spindle, the flier being equipped with a thread guide means and flier wire balance.

Figure 6 is a plan view of the bottom of the flier structure shown in Figure 5.

Figure 7 is a plan view of a flier block having flier wires of the four-arm type.

Figure 8 is a perspective view of my improved flier block provided with wires having drop arms, and,

Figure 9 is a perspective view of a flier wire balance.

Referring to the drawings, and more particularly to Figure 1, there is shown a flier arrangement associated with a bobbin 1, mounted in operative position on a suitable spindle 2, of a conventional winding machine. The bobbin is provided with a head member 3, and a centrally recessed portion 4 adapted to receive a ferrule 5, 10 having an aperture 6 through which the flier foot is inserted. The flier block, designated generally by numeral 7, comprises a centrally apertured body portion 8 having a base portion 9 and a head portion 10. Between the base and 15 head portions, there is provided a peripheral flange 11 constructed and arranged to form a seat for the flier wire support member.

Referring to Fig. 4, it will be noted that the base of the body portion is formed with an eccentric foot member 12, and that the head portion 10 is in the form of a circular flange. The peripheral flange 11, between the base and head portions, is provided with an enlarged portion or collar 13 of slightly greater diameter than that 20 of the main body portion and straight sides 14, the purpose of the arrangement of the collar and straight sides 14 being described more fully hereinafter.

The flier wire support member comprises a 30 plate 15 having a central aperture 16, the diameter of which is substantially equal to the outside diameter of collar 13. The ends 17 of the plate are bent back upon the body portion to form slots or grooves 18 adapted to receive the arms 35 19 of the flier wires. It will be noted that the end members 17 are formed with cut-out portions as at 20, and that the free ends 21 are bent downwardly in overhanging relationship with the body portion of the plate so that the 40 wires are prevented from accidental displacement out of the slots or grooves 18.

In order to securely clamp the flier wire support member in operative position on the body of the flier block, there is provided a cap or 45 clamping plate, designated generally by numeral 22. The cap is formed with an interior recessed portion 23 of substantially the same configuration as the peripheral flange 11, the depth of the recessed portion being approximately equal to 50 the thickness of the flange. The body portion of the cap is formed with projections or extensions 24, which extend outwardly from the recessed portion in a horizontal plane at either side of the straight portions 25 of the recess.

55 In assembling the block, the flier wire support member 15 is placed in seated position on the upper surface of the peripheral flange, recess 16 of the support member fitting over the collar 13 in a fairly snug fit so that lateral movement of 60 the plate 15 with respect to the block is prevented. Cap member 22 is then inserted over the eccentric foot 12 and upwardly into contact with the lower surface of the peripheral flange, the straight sides 25 of the recessed portion of 65 the cap being adjacent straight sides 14 of the flange so that when the flange is seated in the recess, rotation of the cap is prevented. After the parts are in the assembled position, the extensions 24 are attached to the under surface of 70 the flier wire support member, as by spot welding. It will be appreciated that by assembling the parts of the flier block in the manner above described, and particularly by reason of the arrangement of the body portion of the block and 75 the clamping cap or plate, that an extremely

rugged structure is provided, and further that the parts are not liable to become separated, due to vibration or other causes, even after long and continued use.

When it is desired to use the improved flier 5 with a bobbin, as shown in Fig. 1, the flier wires may be attached thereto by twisting or entwining the arms thereof in the vicinity of the central block engaging portions of the wires, the arms 19 being inserted in the slots or grooves 18 beneath the downwardly turned ends 21 of the end members 17 of the flier wire support member. By reason of the additional support afforded by the plate 15 to the flier wires from their points of attachment to the block outwardly in the direction of the drop arms or eyes, together with the maintenance of the arms in the spread position by means of the end members 17, undue flexing of the flier wires out of their normal position in a substantially horizontal plane is prevented with the result that the desired uniform tension can be applied to the thread at all times during the winding operation.

It has been found, under certain conditions of use, that the arms of the flier wires have a tendency to flex downwardly into contact with the upper surface of the bobbin head or the peripheral edge thereof. During the winding operation, it will be appreciated that as the thread unwinds it moves up and down the bobbin between the head portions and that the angle of takeoff is constantly changing. When large bobbins are used, as the diameter of the package decreases, the thread being unwound in the vicinity of the top of the bobbin contacts the edge of the bobbin head causing the flier wires to flex downwardly, thus increasing the tension on the thread. In order to overcome objectional flexing of the flier wire arms and to compensate for the variation in the angle of take-off of the thread, I have provided means associated with the flier, adapted to guide the thread in a pre-determined path of travel to the eyes of the flier wires.

Referring to Figs. 5 and 6, a thread guide wire 26, of larger gauge than the flier wires, is attached to the under side of the flier wire support member 15. The thread guide member comprises a vertical arm 27 having an eyelet 28 formed thereon and a horizontal portion 29, which terminates in a hook end 30. In order to securely mount the guide member on the flier wire support, the body portion of support 15 is provided with slots 31 formed by cutting and pressing out the material between the cuts of the body of the plate. Near the ends of the plate, lugs 32 are struck out therefrom, the lugs being adapted to receive the horizontal arms 29 of the guide wire. As shown in Fig. 6, the guide wire is adapted to be positioned on the under side of the flier wire support member by inserting the hook 30 in one of the slots 31 and sliding the arms 29 underneath one of the lugs 32, the overhanging portion of the lugs being of sufficient length to prevent accidental displacement of the guide wire 60 arm from beneath the lug.

In connection with the arrangement shown in Figs. 5 and 6, it will be noted that a flier wire of the double arm type is used in combination with the thread guide. The flier wire, as more clearly 70 shown in Fig. 6, is provided with a central block engaging portion and the arms thereof are twisted as at 33, to provide tight engagement of the wire with the flier block. When a single flier wire of this type is used, it is advisable to pro- 75

vide means for balancing the block, that is, means to compensate the unbalanced forces due to the projection of the flier arms on the same side of the support plate.

- 5 One method of balancing the block, as here shown, is to provide a balance member, designated generally by numeral 34, Fig. 9, in the form of a loop having straight sides 35, the free ends of the loop terminating in hooks 36 adapted for 10 engagement with one of the ends 17 of the flier wire support member. The flier wire balance may be conveniently attached to the support 15 by overlapping the free ends of the sides 35 and inserting hooks 36 underneath the turned down ends 17 of the flier wire support member, in seated position within slots 18. It will be appreciated that the required balancing effect may be obtained in other ways. For example, the block 20 may be fitted with duplicate wires, one pair being used at a time, and after they have become worn, the other set may be used before it is necessary to rewire the block.

With reference to the operation of the arrangement shown in Fig. 5, and more particularly the 25 function of the thread guide member 26, it will be noted that as the bobbin is unwound, the thread 37 being taken off in the vicinity of the top of the bobbin is directed downwardly through eyelet 28 and vertically upward as at 38 through eyelet 39 of the flier wire. Since the vertical arm 27 of the guide wire projects beyond the bobbin head 2, and extends downwardly a substantial distance below the under surface of the head, the thread 38 is always directed in a predetermined 35 path through eyelet 19, regardless of the angle of take-off from the bobbin. By means of the guide, compensation is effected for the variation in the angle of take-off and flexing of the flier wires downwardly into contact with the upper 40 surface of the bobbin head is prevented.

Referring to Fig. 7, there is shown a modified form of attaching flier wires to the flier block. In this arrangement, the wires are each provided with a central block engaging section 39 and offset portions 40, the offset portions being adapted for 45 interlock and hold the flier wires in seated position in the peripheral groove between the head 10 of the block and the peripheral flange 11. Under certain conditions of operation, the flier 50 may be equipped with two guide members 26, as shown in Fig. 8, the desired tension being obtained without the necessity of using flier wires.

It will now be appreciated that I have provided an improved flier block arrangement of general 55 application in connection with bobbins having relatively large head portions. The flier of the present invention is designed for the purpose of readily adapting it for use under different conditions of service, that is to say, it can be used with 60 wires of the so-called double arm or four-arm type, and when wired in the manner herein suggested, provides uniform tension on the thread at all times during the winding operation.

While I have shown and described the preferred 65 embodiment of my invention, I wish it to be understood that I do not confine myself to the precise details of construction herein set forth, by way of illustration, as it is apparent that many 70 changes and variations may be made therein, by those skilled in the art, without departing from the spirit of the invention, or exceeding the scope of the appended claims.

I claim:

- 75 1. A flier for spinning machines and the like, comprising a centrally apertured body member

having base and head portions, a peripheral flange formed on the body portion between the base and the head portions, a flier wire support member adapted to fit over the head portion of the flier body in contact with the upper surface 5 of the peripheral flange, and means to securely clamp said support member to the flier body comprising a cap adapted to fit over the base of the flier body against the under surface of the peripheral flange, portions of said cap being attached to 10 the flier wire support member.

2. A flier for spinning machines and the like, comprising a centrally apertured body member having base and head portions, a peripheral flange formed on the body portion between the 15 base and the head portions, a flier wire support member adapted to fit over the head portion of the flier body in contact with the upper surface of the peripheral flange, means formed on said support for attaching flier wires thereto and 20 means to securely clamp said support to the flier body comprising a plate member adapted fit over the base of the flier body against the under surface of the peripheral flange, said plate having a recessed portion adapted to accommodate the 25 flange in seated position therein, portions of said plate being attached to the flier wire support.

3. A flier for spinning machines and the like, comprising a centrally apertured body member having base and head portions, a peripheral 30 flange formed on the body portion between the base and the head portions, a flier wire support member adapted to fit over the head portion of the flier body in contact with the upper surface of the peripheral flange and means to securely 35 clamp said support member to the flier body comprising a cap adapted to fit over the base of the flier body against the under surface of the peripheral flange, portions of said cap being welded to the flier wire support member. 40

4. A flier for spinning machines and the like, comprising a centrally apertured body member having base and head portions, a peripheral flange formed on the body portion between the base and the head portions, a flier wire support 45 member adapted to fit over the head portion of the flier body in contact with the upper surface of the peripheral flange, means formed on said support for attaching flier wires thereto and means to securely clamp said support to the flier body comprising a plate member adapted to fit over the base of the flier body against the under surface of the peripheral flange, said plate having a recessed portion adapted to accommodate the 50 flange in seated position therein, portions of said plate being spot welded to the flier wire support. 55

5. A flier for spinning machines and the like, comprising a centrally apertured body member having a base and a head portion, a foot member on said body adapted for insertion into the head of a bobbin, a peripheral flange formed on the body between the foot member and head portion, a flier wire support member adapted to fit over the head portion of the flier body in contact with the upper surface of the peripheral flange, means 60 formed on said support for attaching flier wires thereto, and means to securely clamp said support member to the flier body comprising a cap adapted to fit over the base of the flier body against the under surface of the peripheral flange, 65 portions of said cap being attached to the flier wire support member. 70

6. A flier for spinning machines and the like, comprising a centrally apertured body member having a base and a head portion formed there- 75

on, an eccentric foot member on said body adapted for insertion into the head of a bobbin, a peripheral flange formed on the body of the block between the eccentric foot and head portion, a fier wire support member adapted to fit over the head portion of the fier body in contact with the upper surface of the peripheral flange, means formed on said support for attaching fier wires thereto and means to securely clamp said support to the fier body comprising a plate member adapted to fit over the base of the fier body against the under surface of the peripheral flange, said plate having a recessed portion adapted to accommodate the flange in seated position therein, portions of said plate being attached to the fier wire support.

7. A fier for spinning machines and the like, comprising a centrally apertured body member having a base and a head portion, a foot member on said body adapted for insertion into the head of a bobbin, a peripheral flange formed on the body between the foot member and head portion, a fier wire support member adapted to fit over the head portion of the fier body in contact with the upper surface of the peripheral flange, said support member having a substantially flat body portion, the free ends thereof being bent backwardly upon the body to form slots adapted to receive the arms of a fier wire and means to securely clamp said support member to the fier body comprising a cap adapted to fit over the base of the fier body against the under surface of the peripheral flange, portions of said cap being attached to the fier wire support member.

8. A fier for spinning machines and the like, comprising a centrally apertured body member having a base and a head portion, a foot member on said body adapted for insertion into the head of a bobbin, a peripheral flange formed on the body between the foot member and head portion, a fier wire support member adapted to fit over the head portion of the fier body in contact with the upper surface of the peripheral flange, said support having a substantially flat body portion, the free ends thereof being bent backwardly upon the body to form slots adapted to receive the arms of the fier wire, and means to securely clamp said support to the fier body comprising a plate member adapted to fit over the base of the fier wire against the under surface of the peripheral flange, said plate having a recessed portion adapted to accommodate the flange in seated position therein, portions of said plate being attached to the fier wire support.

9. A fier for spinning machines and the like, comprising a centrally apertured body member having a base and a head portion, a foot member on said body adapted for insertion into the head of a bobbin, a peripheral flange formed on the body between the foot member and head portion, a fier wire support member adapted to fit over the head portion of the fier body in contact with the upper surface of the peripheral flange, said support member having a substantially flat body portion, the free ends thereof being bent backwardly upon the body to form slots adapted to receive the arms of a fier wire, means for attaching a guide wire to the under surface of the fier wire support comprising a slot adapted to receive the free end of the guide wire and a lug struck out from the body portion in the vicinity of the end of the body, said lug being adapted to overhang a portion of the guide wire arm and prevent lateral movement there-

of and means to securely clamp said support member to the fier body comprising a cap adapted to fit over the base of the fier body against the under surface of the peripheral flange, portions of said cap being attached to the fier wire support member.

10. A fier for spinning machines and the like, comprising a centrally apertured body member having a base and a head portion, a foot member on said body adapted for insertion into the head of a bobbin, a peripheral flange formed on the body between the foot member and head portion, a fier wire support member adapted to fit over the head portion of the fier body in contact with the upper surface of the peripheral flange, said support member having a substantially flat body portion, the free ends thereof being bent backwardly upon the body to form slots adapted to receive the arms of a fier wire, means for attaching a guide wire to the under surface of the fier wire support comprising a slot adapted to receive the free end of the guide wire and a lug struck out from the body portion in the vicinity of the end of the body, said lug being adapted to overhang a portion of the guide wire arm and prevent lateral movement thereof and means to securely clamp said support to the fier body comprising a plate member adapted to fit over the base of the fier body against the under surface of the peripheral flange, said plate having a recessed portion adapted to accommodate the flange in seated position therein, portions of said plate being attached to the fier wire support.

11. A fier for spinning machines and the like, comprising a centrally apertured body member having base and head portions, a peripheral flange formed on the body portion between the base and the head portions, a fier wire support member adapted to fit over the head portion of the fier body in contact with the upper surface of the peripheral flange, means formed on said support for attaching fier wires thereto, means for attaching a guide wire to the under surface of the fier wire support comprising a slot adapted to receive the free end of the guide wire and a lug struck out from the body portion in the vicinity of the free end of the body, said lug being adapted to overhang a portion of the guide wire and prevent lateral movement thereof and means to securely clamp said support member to the fier body comprising a cap adapted to fit over the base of the fier body against the under surface of the peripheral flange, portions of said cap being attached to the fier wire support member.

12. A fier for spinning machines and the like, comprising a centrally apertured body member having base and head portions, a peripheral flange formed on the body portion between the base and the head portions, a fier wire support member adapted to fit over the head portion of the fier body in contact with the upper surface of the peripheral flange, means formed on said support for attaching fier wires thereto and means to securely clamp said support to the fier body comprising a plate member adapted to fit over the base of the fier body against the under surface of the peripheral flange, said plate having a recessed portion adapted to accommodate the flange in seated position therein and flanged portions extending outwardly beyond said recess, the flanged portions being welded to the fier wire support.

13. A fier for spinning machines and the like,

comprising a centrally apertured body member having a base and a head portion, a foot member on said body adapted for insertion into the head of a bobbin, a peripheral flange formed on the body between the foot member and head portion, a flier wire support member adapted to fit over the head portion of the flier body in contact with the upper surface of the peripheral flange, said support having a substantially flat body portion, the free ends thereof being bent backwardly upon the body to form slots adapted to receive the arms of the flier wire, and means to securely clamp said support to the flier body comprising a plate member adapted to fit over the base of the flier wire against the under surface of the peripheral flange, said plate having a recessed portion adapted to accommodate the flange in seated position therein and flanged portions extending outwardly upon said recess, the flanged portions being welded to the flier wire support.

14. A flier for spinning machines and the like, comprising a centrally apertured body member having a base and a head portion formed thereon, an eccentric foot member on said body adapted for insertion into the head of a bobbin, a peripheral flange formed on the body of the block between the eccentric foot and head portion, a flier wire support member adapted to fit over the head portion of the flier body in contact with the upper surface of the peripheral flange, means formed on said support for attaching flier wires thereto, a flier wire having a central block engaging section and arms extending outwardly therefrom mounted upon the block, the arms of the wires being entwined in the vicinity of the block, the portions of the arms therebeyond being in engagement with the wire retaining means, means to securely clamp said sup-

port to the flier body comprising a plate member adapted to fit over the base of the flier body against the under surface of the peripheral flange, said plate having a recessed portion adapted to accommodate the flange in seated position therein, portions of said plate being attached to the flier wire support.

15. A flier for spinning machines and the like, comprising a centrally apertured body member having a base and a head portion formed thereon, an eccentric foot member on said body adapted for insertion into the head of a bobbin, a peripheral flange formed on the body of the block between the eccentric foot and head portion, a flier wire support member adapted to fit over the head portion of the flier body in contact with the upper surface of the peripheral flange, means formed on said support for attaching flier wires thereto, a flier wire having a central block engaging section and arms extending outwardly therefrom mounted upon the block, the arms of the wires being entwined in the vicinity of the block, the portions of the arms therebeyond being in engagement with the wire retaining means, means for attaching a guide wire to the under surface of the flier wire support comprising a slot adapted to receive the free end of the guide wire and a lug struck out from the body portion in the vicinity of the free end of the body, said lug being adapted to overhang a portion of the guide wire arm and prevent lateral movement thereof and means to securely clamp said support member to the flier body comprising a cap adapted to fit over the base of the flier body against the under surface of the peripheral flange, portions of said cap being attached to the flier wire support member.

MICHAEL J. McHALE.
